MIXING APPARATUS

Edward M. O'Neill, San Francisco, Calif., assignor
to Union Machine Company, San Francisco,
Calif., a corporation of California

Application October 16, 1939, Serial No. 299,677

2 Claims. (Cl. 259—1)

This invention relates to an apparatus for making mixtures; such for example as for mixing the ingredients of paints, lacquers, enamels or the like, in order to secure a predetermined color.

It is clear that in order to ensure availability of all the various tints, or colors of such paints, which are ready mixed, it is necessary to provide a very large stock. It is one of the objects of this invention to obviate the necessity of carrying such large stocks, and especially by providing a color mixer, in which any of a limited number of so-called "primary" colors can be used in a wide variety of compositions. Thus with as few as fifteen selected colors, many thousands of colors can be produced.

By the aid of this invention, the previously determined formula for each color combination, prescribing use of some of the ingredient colors provided, may be readily followed in a simple manner. It is only necessary to use the prescribed quantities of each of the constituent colors; and prepared tabulations, for various sized paint cans, may be utilized, setting forth the measured amounts of each necessary constituent color to be included in the final mixture.

It is another object of this invention to make it possible, in a simple manner, to perform these measuring operations.

In general, the apparatus for performing the mixing operation may conveniently incorporate a table, supporting the cans in which the constituent colors are located, and having provisions for positioning any one of the cans at a discharging position, where a stationary mixing table is provided. The containers or cans should be capable of being readily removed and replaced in the apparatus, as well as to be readily controlled to discharge the desired amount of its paint or color. It is accordingly another object of this invention to provide a can or container structure that fulfills these requirements in a very satisfactory manner.

In order to ensure uniformity in results, it is essential that the constituent colors be thoroughly agitated immediately prior to the mixing operation. It is still another object of this invention to provide an effective and reliable agitator mechanism and agitator drive, that is simple, inexpensive and capable of rapidly and simultaneously agitating all of the colors.

This invention possesses many other advantages, and has other objects which may be made more easily apparent from a consideration of several embodiments of the invention. For this purpose there are shown a few forms in the draw-

ings accompanying and forming part of the present specification. These forms will now be described in detail, illustrating the general principles of the invention; but it is to be understood that this detailed description is not to be taken in a limiting sense, since the scope of the invention is best defined by the appended claims.

Referring to the drawings:

Figure 1 is an elevation of an apparatus incorporating the invention;

Fig. 2 is a top plan view of the apparatus shown in Fig. 1, a portion of the apparatus being broken away in order better to expose some of the elements thereof;

Fig. 3 is a sectional view, taken along plane 3—3 of Fig. 2;

Fig. 4 is a fragmentary sectional view, taken along plane 4—4 of Fig. 2;

Fig. 5 is a sectional view, taken along plane 5—5 of Fig. 3;

Fig. 6 is a sectional view, taken along plane 6—6 of Fig. 5;

Fig. 7 is a sectional view, taken along plane 7—7 of Fig. 5;

Fig. 8 is a sectional view, taken along plane 8—8 of Fig. 7;

Fig. 9 is an enlarged fragmentary view, taken along plane 9—9 of Fig. 3, the agitator shaft being shortened in order to reduce the size of the figure, and the container being omitted;

Fig. 10 is an enlarged sectional view, taken along plane 10—10 of Fig. 2;

Fig. 11 is a sectional view taken along plane 11—11 of Fig. 3;

Fig. 12 is a sectional view taken along plane 12—12 of Fig. 3;

Fig. 13 is a view, mainly in elevation, illustrating the manner in which the color or tint containers are supported by the aid of a table;

Fig. 14 is a sectional view, taken along the plane 14—14 of Fig. 13;

Fig. 16 is a fragmentary enlarged front elevation of the valve mechanism utilized in connection with the container illustrated in Fig. 13;

Fig. 17 is a sectional view taken along plane 17—17 of Fig. 16;

Fig. 18 is an elevation of a modified form of container that may be utilized in connection with the apparatus illustrated in Figs. 1, 2 and 3; and

Fig. 19 is a fragmentary sectional view taken along plane 19—19 of Fig. 18.

The apparatus as a whole is generally shown in Figs. 1, 2 and 3. In these figures, a flat table

1 is illustrated which serves to support a series of containers 2 detachably. This table 1 may conveniently be made from sheet metal. The supporting structure may be described especially in connection with Figs. 1 and 3. The table 1 has a generally circular configuration and may be provided with a central sleeve 3 (Fig. 3). Overlying the table 1 and vertically spaced above it, is another sheet metal member 4, serving as a bracket or shelf for supporting some of the parts of the apparatus, as hereinafter described. The bracket 4 as well as the table 1 may be welded to opposite ends of the sleeve or pipe 3. The member 4 is arranged to overlie and close the opening through the sleeve 3.

The table structure incorporating the parts 1, 3 and 4, is arranged to be angularly adjustable about the axis 5 of a pedestal 6. This pedestal 6 extends upwardly into the sleeve 3 where it serves as a journal bearing for the sleeve. Pedestal 6 may be in the form of a hollow pipe, capped at its upper end by a cap member 7 having a convex top surface. The bracket member 4 rests by gravity at its center, upon the cap 7; and the sleeve 3 has a running fit over the pedestal 6. In this way the table structure may be angularly adjusted manually or otherwise, as required in the use of the apparatus.

The pedestal 6, as shown most clearly in Fig. 1, may be supported in a base 8 having a wide flange 9 by the aid of which it may be secured to a supporting surface, such as a floor 10. Thus the entire apparatus may be conveniently located in a paint shop, or other locations where it is desired to provide a definite mixture, incorporating liquid, such as paint, from any one or more of the liquid containers 2.

The arrangement is such that by rotation of the structure, any of the containers or cans 2 may be brought into a desired position for discharging an ingredient or constituent from the can. For this purpose the cans or containers 2, as shown most clearly in Fig. 2, are arranged in an annular manner about the axis 5 of rotation of the table structure. In the present instance provisions are made for fifteen containers 2 to be releasably supported by the table 1. These containers may be in the form of conventional paint cans, each one appropriately labeled with the number or name of the color constituent which it carries. Each of the cans or containers 2 is furthermore provided with some valve means to permit discharging of the color constituent into any desired container, such as illustrated at 11, Figs. 1, 2, 3 and 5. By angular adjustment of the position of the table, any one of the containers 2 may be brought in appropriate cooperating position with respect to the container or can 11. The manner in which this container or can 11 is supported will be described hereinafter.

Each of the containers 2, as shown in Figs. 2, 13 and 14, depend through a respective aperture 16, in table 1. This is rendered possible by the aid of exterior supporting lugs or projections 12 fastened to the cans and adapted to rest upon the top surface of the table 1. These projections 12 are shown in this instance as formed integrally with a sheet metal band 13 tightly embracing the container 2 adjacent the top thereof. Thus for example, the ends of the band 13 may be provided with the ears 14 through which the tightening bolt 15 passes.

The projections 12, adapted to rest on the top of table 1, thus limit downward movement of the containers 2 through the corresponding apertures

16 formed in the table 1. Upward movement of the containers 2 is limited by the ball-lugs 17, which engage the lower surface of the table 1.

By providing the aperture 16 with radially extending slots 18, 19 and 20 (Fig. 14) the projections 12 as well as the ears 14 and bolt 15 may be passed upwardly through these slots from below the table 1. Then the container 2 may be turned in a counterclockwise direction so as to place the projections 12 and the ears 14 out of alignment with their respective slots. The vertical space between the lower surfaces of the projections 12 and the upper surfaces of the lugs 17 is made substantially the same as the thickness of the table 1. In order to limit the counterclockwise movement of the containers 2, stop pins such as illustrated at 21 may be utilized, fastened to the table 1. In case the liquid or other material in the containers 2 is agitated by paddles, the tendency for the containers to rotate with the liquid is thus appropriately nullified.

As thus far described, it is apparent that the table structure 1, 3, 4, may be angularly adjusted to bring any one of the containers 2 into cooperative relation with a can or container 11 so as to enable the operator to permit the flow of liquid from any one of these containers into the can 11. The control of the passage of liquid out of the containers 2 is provided by the aid of valve structures located near the bottom of the cans. These valves may be best described in connection with Figs. 13, 15, 16 and 18.

Thus there is provided a valve body 22, which has an arcuate rear surface 23 conforming with the exterior surface of the container 2. Interposed between the body 22 and the container 2 may be a sealing gasket 24, such as of cork or the like. The body 22 may be held firmly in place near the bottom of the container 2 by the aid of the flexible clamping bands 25 and 26. These clamping bands are provided with loops such as indicated at 27, extending around the posts 28 formed integrally with the body member 22. The free ends of the bands 26 and 25 are each provided with ears 29 through which passes the tightening bolt 30. In this way the flexible bands 25 and 26 are held tightly in place, and the valve structure is thus secured to the can.

The body 22 is provided with a through port 31, placed in communication with the interior of the container 2, in a manner to be described. The outer face 32 of the valve body 22 is shown as being provided with the bosses 35 and 37, having flat surfaces. Port 31 extends through boss 35. Forming a closure for the port 31 is a member 33. This member 33 in the form of a metal plate, lying closely over the boss 35, is adapted to move in a direction transverse to the port 31, and is shown as provided with a lower knife edge 34. This knife edge 34 ensures that the discharge through the port 31 will be cut off sharply, as closure 33 moves downwardly past the port. The lower edge of boss 35 is formed with a converging point 48 to guide the flow of liquid in a more uniform stream. Closure member 33 is urged laterally against the boss 35 by resilient means in a manner to be hereinafter described. In this way it is ensured that a tight closure of the valve is secured.

Closure member 33 is pivotally mounted on a stationary stud 36 threaded into the body 22, in the center of boss 37. Resilient means are provided for urging the closure member 33 in a

clockwise direction to the closed position illustrated in Fig. 16. This clockwise rotation, however, is limited by engagement of a projection 39 formed on the closure member 33, with a stop 29 formed integrally with the body 22. Closure member 33 may also be provided with a finger piece or handle 40 for facilitating the raising of the closure 33 to open position. Furthermore, the body 22 may also be provided with a rest 41 integrally formed on the body 22, to accommodate the thumb of the operator when he desires to manipulate the closure member 33. In this way, the thumb serves to steady the container 2 during operation of the valve closure 33.

The resilient means for urging the closure 33 to the position of Fig. 16 may be in the form of a helical spring 42. One end of the spring is shown as anchored in a crown nut 43 threaded on the stud 36. The other end of the spring 42 acts upon the closure member 33 adjacent the place where it is pivoted on the stud 36, urging the closure member 33 tightly against the boss 37. By appropriate adjustment of the nut 43 the expansive force of the spring 42 may be varied. The nut 43 may be held in adjusted position as by the aid of cotter pin 44.

In order to urge the closure member 33 against stop 39, the free end 45 of the spring 42 is shown as extended along the closure member 33, and is provided with an end 46 engaging in a recess 47 in the closure member 33. The projection 46 thus serves to connect the closure member 33 with the torsion spring 42. Adjustment of nut 43 also adjusts the torsion of the spring 42. The end 45 also operates as a leaf spring, exerting a transverse force on closure 33, to urge it strongly against boss 35.

The valve structure as just described may be very simply installed on any ordinary can such as a paint can, even when the can is full. Thus the bands 25 and 26 may be encircled around the container 2 in such a place as to position the valve structure in the desired location. Then the bolt 30 can be tightened. The connection into the can 2 can then be provided by laying the container 2 on its side with the valve structure uppermost, and forcing a piercing instrument through the port 31 to form the aperture 49 (Fig. 17) in the wall of the can. This piercing can be made with an awl-like instrument even when the can is filled with liquid, the usual cover of the can being in place. It is intended that this cover be removed after the piercing operation and replaced with a similar cover 50 which has a central packed opening to accommodate the agitator shaft 75. This cover 50 is shown as of the usual paint can variety having cooperating surfaces yieldingly holding the cover 50 in place.

Other ways of supporting the valve structure and of forming the supporting projections on the containers 2 may be utilized. For example, in the form illustrated in Figs. 18 and 19, the container 51 is shown as having sets of supporting projections 52 and 53 fastened, as by soldering, directly on the exterior of the container 51. The vertical spacing between the projections 52 and 53 agrees with the thickness of the table 1. In this instance the container 51 can be supported by projections 52, 53, in such manner that a substantial portion of the container extends upwardly beyond the table 1. However, it may be temporarily dropped downwardly, without removal from the table 1, and maintained in this dropped position by another

series of projections 54 adjacent the top of the can or container 51. During operation of the apparatus the projections 52 and 53 are in use. When it is desired to facilitate loading or lowering the containers, the containers 51 may be dropped to the position determined by the projection 54.

The valve structure in the form illustrated in Figs. 18 and 19 is quite similar to that disclosed in Figs. 13, 15, 16 and 17. However, in this case the valve body 55 is shown as directly soldered to the exterior of the container 51, thus obviating the necessity of any sealing gasket. The knife-like closure member 56 is urged by a helical spring to the closed position illustrated. The end 57 of the helical spring operates in substantially the same manner as the projection 45 of the form previously described. The body 55 is formed with an integral stop 58 cooperating with a bottom edge of the closure 56. A handle in the form of a rod 59 may be provided on the closure member 56 for facilitating manual operation of the closure member 56.

As thus far described, it is evident that by appropriate manipulation of the apparatus, liquid may be caused to be discharged from any selected container 2 into a can or container 11. There will now be described the supporting means for the container 11.

Referring in this connection to Figs. 2, 3, 5, and 12, the container 11 is shown as disposed upon a "mixing" table or platform 60. The container 11 may be of the conventional paint can type, and any of a number of sizes of paint cans can be accommodated on the table 60. It is desirable to ensure, for measuring purposes as hereinafter described, that the bottom 61 of the can 11 lie flat upon the top surface of the table 60, even when the container has a protruding rolled bead 63 at its bottom. Accordingly table 60 is formed with a plurality of annular grooves 62 for accommodating the bead 63. A sufficient number of these annular grooves 62 are provided to take care of the variety of sizes that may be utilized with the machine.

The table 60 is shown as supported by the aid of a rod 64 which is press fitted into a boss 65 formed integrally with the table 60. The rod 64 in turn is supported in a boss 66 formed at the free extremity of a bracket 67. The rod 64 is arranged to have a sliding fit within the boss 66, and may be held in any adjusted vertical position, as by the aid of a thumb screw 68.

The bracket 67, shown in this instance as of ribbed cast construction, is formed at its other extremity with a half socket 68 partially embracing the standard 6. Cooperating with this half socket 68 is a clamping band 69. This clamping band is provided with a projection 70 passing through an aperture formed in the bracket 67. At its other end the band is provided with an ear 71. This ear 71 is in opposed relation to the ear 72 formed on the socket member 68 of the bracket 67. A clamping bolt 73 and thumb nut 74 are utilized for maintaining the bracket structure 67 tightly in place upon the standard 6.

Although the apparatus may be utilized in connection with any free-flowing materials, such as liquids, for facilitating making of mixtures in the container 11, one of its important uses is in the mixing of tints or colors in connection with lacquers, enamels and paints. When so utilized each of the containers 2 may be appropriately labeled or numbered to correspond with

a definite standard color chart. In this way the desired container 2 can be moved to a position where the color or tint from that desired container may be passed into the container 11.

When used in connection with paints it is also quite important to ensure that the constituent or ingredient colors in the fifteen containers 2 may not settle to the bottom of the can. For this purpose an agitator mechanism is provided.

Thus as shown most clearly in Figs. 3 and 9, an agitator spindle 75 is shown as associated with each can or container 2.

Preferably some packing for the spindle 75 is provided for, to ensure that the paint or other liquid will not be splashed through cover 50. Thus as indicated most clearly in Fig. 9, a packing material 16, surrounding spindle 75, may be disposed in a packing housing 17, fastened to the top of the cover 50 as by the flange 18.

The agitator spindle 75 carries at its lower end the agitator paddle 19. This agitator paddle 19 may be formed of a flat metal bar having an intermediate portion 80 fitted into a slot in the end of the spindle 75. The bar 19 on opposite sides of the member 80 may be bent in opposite directions, so that the broad surfaces of the paddle lie in planes oblique to the axis of spindle 75, as illustrated most clearly in Fig. 9. The portion 80 may be brazed in place in the lower end of the spindle 75. The agitator bar 19 is arranged to be disposed adjacent the bottom of the respective containers 2. It is rotated in a counterclockwise direction, by a power transmission which will now be described.

Each of the spindles 75 is provided with a driving pulley structure, shown to best advantage in Figs. 2, 3 and 9. The spindle 75 is shown as detachably connected to the lower end of its corresponding stem 81. The lower end of stem 81 for this purpose is provided with a central threaded aperture 82, within which the threaded end 83 of the spindle 75 may be accommodated. An enlarged recess 84 is provided in the bottom of the stem 81 within which the upper cylindrical portion of the spindle 75 may be accommodated. The shoulder formed at the top of spindle 75 around end 83 seats accurately in the bottom of the recess 84. To facilitate coupling and uncoupling of the spindle 75 from the stem 81, a through aperture 85 may be provided through the upper end of the spindle 75, for the accommodation of a pin to serve as a handle.

Thus, if desired, as for example for purposes of cleaning or filling or replacing any container, the spindle 75 may be disconnected from the stem 81, and then the container 2 with the spindle 75 may be removed as a unit from the table 1.

The stem 81 is journaled within a standard 86 (Fig. 9). This standard is shown as being provided with a lower, reduced portion 87, forming a shoulder 88. This shoulder 88 rests upon the top of the shelf member 4. Standard 86 may be held tightly in place upon the shelf 4 as by the aid of a nut 89, accommodated on the threaded portion 90 of the cylindrical extension 91.

Interposed between the stem 81 and the standard 86 are one or more bearing bushings 92, 93. These bushings may be made of self-lubricating material such as oilite. In order to keep these bushings properly saturated, oil may be supplied to them as through the oiling apertures 94, 95. Oiling aperture 94 connects with an annular recess 96 in standard 86, surrounding the bushing 92. The oiling aperture 95 is in communication with the annular space between the standard 86

and the stem 81. Through this annular space the oil may drop to the lower bearing bushing 93.

The upper end of stem 81 is arranged to be connected to the hub 97 of a driving pulley structure 98. For example, the radial headless set screw 99 may be used to form this driving connection. The pulley 98 may be conveniently formed of a pair of sheet metal disks forming, adjacent their outer edges, a V-groove 100, for the accommodation of a wedge-shaped belt 101. Adjacent the hub 97, stiffener disks 102 may be provided. These disks may be telescoped over or splined to the upper end of the hub 97; and then the hub 97 may be upset at its end to hold the sheet metal elements tightly in place.

As shown most clearly in Fig. 2, a pulley structure 98 is associated with each of the agitator stems 81. The V-belt 101 serves to drive all of the pulley structures 98. For this purpose the V-belt 101 is shown as in driving contact with the outer edges of each of the pulley structures 98. The belt 101 makes a reverse bend, as indicated at 102, so as to pass around a driving pulley 103. This pulley is shown to best advantage in Fig. 10.

The driving pulley 103, due to the reverse bend 102, engages that side of the belt 102 which is out of engagement with the pulley structures 98. Accordingly, this outer surface of the belt 101 is also made wedge-shaped, providing a double V-belt arrangement. All of the agitator structures, for all of the containers 2, are driven in the same direction; that is, in a counterclockwise direction, tending to urge the projections 12 of these containers against the stop pins 21 (Fig. 2).

For driving the pulley 103 and thereby transmitting power to the stems 81, this pulley structure 103 is formed as one element of a step pulley. Another element of the step pulley is pulley structure 104, which is rotated by a source of power. These two pulley structures thus must rotate in unison. They are freely rotatable on a non-rotatable stub shaft 105. The hub of the stepped pulley structure may be provided with oilite bushings 106 adapted to be oiled through the apertures 107. This pulley structure may be restrained against upward axial movement with respect to the stub shaft 105, as by the aid of a collar or washer 108 held in place by spring snap ring 109. The manner in which the stub shaft 105 is supported will be explained hereinafter.

A source of power, such as a small vertical electric motor 110 (Figs. 1, 2 and 11) may be belt connected to the pulley element 104. For supporting the motor 110, a bracket structure 111 is utilized, having four upright arms 112. At the top of each of these arms there is a boss 113 for the accommodation of the studs 114 which pass into the end frame 115 of the motor 110. Nuts 116 and 117 serve to maintain the motor 110 securely in place on top of the arms 112.

The motor shaft at its lower end, carries a V-pulley 118. This pulley is in driving relation with the pulley structure 104 as by the aid of the V-belt 119.

There is thus obtained a double reduction from the motor shaft to the agitator mechanism. One reduction is secured by the aid of the small driving pulley 118 on the motor shaft driving a comparatively large diameter driven pulley structure 104; and the small pulley structure 103, joined to pulley 104, drives the larger pulley structures 98. The paddles 19 are thus given a rate of rotation that is not too violent, without the necessity of reduction gearing.

Provisions are made for tightening both of the belts 101 and 119 simultaneously. It is clear that

if the axis of the stub shaft 105 be moved radially inwardly, such a movement will serve to tighten the belt 101, while belt 119 would be loosened. But if at the same time the motor 110 is moved sufficiently in a direction upwardly as viewed in Fig. 2, the belt 119 may be nevertheless tightened. Both of these tightening movements can be obtained by providing a floating support for shaft 105 and by moving the motor 110 upwardly as viewed in Fig. 2.

For this purpose, the stub shaft 105 is shown as carried by a disk 122, as by being firmly fixed in a boss 120, formed integrally with the disk 122. The shaft 105 is held tightly in said boss 120, as by being riveted over at its end 121. Disk 122 is mounted for angular motion about an eccentric axis 123 parallel to, but spaced from the axis of the boss 120.

In order to provide this supporting axis 123, the eccentric disk 122 is provided with another boss 124, into which is fastened a stub shaft 125. This stub shaft has an enlarged journal portion 126 journaled in the shelf member 4. It also is provided with a threaded end 127. Over this end is disposed a nut 128, acting against a limiting washer or collar 129 arranged below the shelf 4.

As indicated most clearly in Fig. 2, and considering that the axis 123 is fixed, an upward movement of the motor 110 will serve simultaneously to move the stub shaft 105 angularly about the axis 123, in an upward direction. This movement of the motor 110 can be made sufficiently great to take the slack out of both of the belts 101 and 119, as hereinbefore described.

The manner in which the motor 110 may be moved for accomplishing this result is illustrated to best advantage in Figs. 2 and 11. Thus the bracket 111 which supports the motor 110, is shown as provided with a pair of feet 129 and 130, resting on shelf member 4. These feet are slotted for the accommodation of bolts 131, 132, which pass through appropriate apertures in the shelf member 4. These bolts are provided with the nuts 133, operating to clamp the feet 129, 130 to member 4. When the nuts, however, are loosened, the bracket 111 may be moved within the limits prescribed by the slots, as by the aid of an adjusting bolt 134 (Figs. 2 and 3). This adjusting bolt is journaled in a standard 135, fastened as by the aid of an integrally formed stud 136 to the top of the shelf member 4. The adjusting bolt 134 threadedly engages the threaded boss 137 formed integrally with the bracket 111. When the apparatus is used for mixing paints or lacquers or the like, it is advantageous to make it possible to pass either a paint or a lacquer thinner into the container 11, supplemental to the ingredients from container 2. Accordingly tanks or cans are provided, appropriately supported on top of the shelf member 4, for this purpose. Thus a container 138 for paint thinner may be supported on the shelf 4 as by the aid of the brackets 139. A similar container 140 for lacquer thinner may be supported on the other side of the center of the shelf member 4. Leading from these containers are the pipe conduits 141 and 142 which converge adjacent the edge of table 1. The conduits 141 and 142 thence extend through appropriately formed apertures in the shelf 4 and the table 1. They may be clamped together as by the aid of several twin clamps 143 beneath the table 1. At their lower extremity, they accommodate the manually operable plug valves 144. Thus these plug valves have outlet spouts extending downwardly in position to discharge the thin-

ner into the container 11, when the table 1 is turned angularly to the proper position.

It is advantageous to make it possible to measure or somehow indicate or determine the amount of liquid discharged respectively from those containers 2 which carry the color of tints or other liquid needed to be included in the desired mixture. For this purpose a float gauge arrangement is utilized, shown to best advantage in Figs. 3, 5, 6, 7 and 8. By the aid of this arrangement the prescribed amount of the ingredients to be included in the mixture may be quite accurately gauged, and the delivery of the tint or the color or other liquid may be stopped as soon as the required amount is passed into the container 11.

For this purpose a float 145 (Fig. 5) may be utilized, which is carried at the lower end of a float stem or pin 146. The float 145 and the stem 146 are preferably made from as light material as practicable, to ensure a high degree of accuracy. For example, the float 145 may be made of balsa wood, and the stem 146 may be made of thin aluminum tubing.

The top surface 147 of the float stem 146 may be utilized as a gauging surface in a manner to be hereinafter described. The float stem 146 is guided so as to permit the float 145 readily to reach a position corresponding to the level of the liquid 148 in container 11. For this purpose the float stem 146, as shown most clearly in Fig. 7, is guided by a guide bushing 149. This guide bushing is hollow. At its upper end it is provided with a flange 150 having a rounded inner edge serving as a guide aperture, and providing an easy sliding fit for the stem 146 at the top of the guide bushing. The guide 149 is firmly held in place on a bracket 151, in a manner to be hereinafter described. This bracket 151 is supported on an upright rod 152, press-fitted at its lower end in the boss 153 on table or platform 60. The bracket 151 is provided with a boss 154 through which the rod 152 extends. The boss 154 is accurately reamed in order to provide a good fit between the rod 152 and the bracket 151. This bracket 151 may be held in any vertically adjusted position, as by the aid of the thumb screw 155.

As shown most clearly in Fig. 7, the guiding sleeve 149 has a reduced portion 156 that passes through an aperture in the boss 157 formed on the bracket 151. In this way the guide 149 has an annular shoulder formed on it which contacts the top surface of the boss 157. The lower extremity of the reduced portion 156 is threaded for the accommodation of a knurled nut 158 for holding the guide sleeve 149 securely in place. This knurled nut provides a lower guiding aperture for the stem 146; thus the nut has a flange 159, having a rounded inner edge that cooperates with the stem 146.

Containers of various sizes may be substituted for container 11. Thus pint, quart and gallon cans may be utilized. In some instances the float structures just described might also be changed to correspond with the size of the cans. By the aid of the knurled nut 158 it is a simple matter to replace the float stem guide with another one to fit the particular float structure utilized. The annular recesses 62 are especially useful when a small can is used in lieu of can 11. The recess for the lower beads of such small cans ensures that these cans will be in proper cooperative position with respect to the float gauge structure.

The top gauging surface 147 of the float structure rises as the level of the liquid 148 rises in the container 11. This gauging surface 147 is arranged to cooperate with any of a plurality of scales formed on a gauge rod 160, placed adjacent stem 146. In the present instance this gauge rod is shown as square in section, but having a lower rounded portion 161 and reduced rounded portion 162. This rounded portion 162 may be accommodated within an aperture 163 in the boss 157 of bracket 151. The gauge rod 160 is placed close to the float stem 146 so that it is comparatively easy to sight along the gauging surface 147 and make a reading on the gauge rod 160. Furthermore, it is possible readily to turn the bar 160 about its axis in aperture 163, so as to make it possible to utilize different scale markings with the gauging surface 147. For example, the smaller the can, the less volume is represented by a unit of variation in liquid level. Thus in the present instance, each of the four sides of the rod 160 may be marked with appropriate scale markings, such as 164 corresponding respectively to the sizes of the container 11 that is disposed on the mixing platform 60.

In order to facilitate the measurement of the liquid entering into container 11, an adjustable stop collar 165 may be utilized, to cooperate with the gauging surface 147. This stop collar may be made of light material such as aluminum. At its lower edge, it carries a flange 166 overlying the gauging surface 147. The collar 165 may be readily adjusted along the rod 160 and held in adjusted position as by the aid of the strong flat spring 167 disposed within the collar and fastened thereto as by the rivet 168. The free ends of the spring 167 press against one of the flat surfaces of the square rod 160. In this way the spring 167 urges the internal cylindrical surface 169 of the collar 165 against the corners 170, 171 of the rod 160. Thus collar 165 is maintained in place by friction.

The lower surface of flange 166 of collar 165 may be brought to the desired graduation mark on scale 164, as prescribed by the mixture to be obtained, and liquid may then be discharged from a container 2 and until the level of the liquid or paint in container 11 causes the gauging surface 147 to arrive at the lower surface of flange 166.

For guard purposes, the belt and pulley transmission may be covered as by the aid of a guard 172 (Figs. 1, 2 and 3). This guard 172 is in the form of a hollow annulus open at the bottom. It is telescoped within the upstanding flange 173 of the member 4 and the annular guard covers all of the pulley structures 98. It may be provided with appropriate apertures to permit the passage of the belt 101 to the pulley 103; as well as for the conduits 141 and 142 of the containers 138, 140. The guard 172 may be held in place as by the aid of one or more clips 175 (Fig. 2) fastened to the top of the shelf member 4.

The apparatus is designed generally for facilitating the making of mixtures from specified ingredients; it is especially applicable to the mixing of paints, varnishes, lacquers, enamels, etc. The manner of use for this specific purpose may now be set forth.

For example, it has been difficult to match exactly the colors for automobile lacquer finishes

unless a large stock of colors is kept. By appropriate choice of color ingredients in the fifteen containers 2, it is possible to match such colors very closely. The colors and the formulas required to produce them by the aid of any group of the fifteen constituents may be listed in a color table. Such a table may list the ears by name, color, and year; and associated with each of these, may be a table, stating where the collar 165 must be placed with the proper scale, in succession for each ingredient to be added.

The manner of setting the bracket 151 at the correct height along rod 152, prior to these measurements, may also be described. First of all, the platform 60 is placed at a convenient height to correspond with the size of can 11, the top edge being set close under the valves on containers 2. The float 145 is then dropped to the bottom of the empty can 11. Gauge rod 160 is turned so that the proper scale for the size of can 11 is in position behind the pin or stem 146. The bracket 151 is now set so that the zero mark on the scale will be slightly above the gauging surface 147 (of about the order of one fourth of an inch). Clamp screw 155 is then tightened. Collar 165 is moved to the zero mark. The table 1 is now angularly moved until petcocks 144 are directly over the can 11. That cock is opened which corresponds to the proper thinner container 138 or 140 (Fig. 2). The cock 144 is opened and enough thinner is passed into can 11 to bring float pin 146 up to the zero position of the gauge collar 165. The operator is now ready to consult his color tables, setting thereafter the collar 165 to agree with the tabulation for the first ingredient. This operation of setting the collar 165 is repeated according to the formula book until the required number and amounts of tinting colors fill the can 11.

The thinner added at the beginning of the operation is not of sufficient amount to prevent closing the can 11 with the usual friction cover.

Some care must be taken to position float 145 at the side of can 11. It must be so located so that it can be readily removed from a full can 11 without disturbing it. If the float is not located properly, incoming color will pour on top of the float and thereby disturb its operation.

What is claimed is:

1. In apparatus of the character described, a table having a circular aperture therein, the edge of said aperture having a plurality of slots therein, a container adapted to enter into said aperture; projections carried by said container adapted to pass through said slots, and to contact one surface of the table, and one or more projections on said container adapted to lie against the opposite surface of the table.

2. In apparatus of the character described, a table having a circular aperture therein, the edge of said aperture having a plurality of slots therein, a container adapted to enter into said aperture, projections carried by said container adapted to pass through said slots, and to contact one surface of the table, and one or more projections on said container adapted to lie against the opposite surface of the table, said projections serving to hold said container firmly to the table by close contact between the projections and the table surfaces.

EDW. M. O'NEILL.
